(57) CLAIM

The ornamental design for equipment for standing and holding paper, as shown and described.

DESCRIPTION

FIG. 1 is a perspective view of the top, front and right side of equipment for standing and holding paper showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view, the left side elevational view being a mirror image thereof; and,

FIG. 7 is a perspective view showing the equipment in use. The elements shown in broken lines are for illustrative purposes only and form no part of the claimed design.
